THREAD CONTROLLING MECHANISM

Robert H. Lawson, Pawtucket, R. I., assignor to
Hemphill Company, Central Falls, R. I., a cor-
poration of Massachusetts

Application March 22, 1932, Serial No. 600,430

29 Claims. (CL 66—146)

This invention relates to a new and improved mechanism for governing the thread or yarn tensions, being herein shown as applied to a knitting machine of the type disclosed in the Lawson and Lawson Patent 1,702,608, February 19, 1929, although the invention is applicable to other types of knitting machines and to other types of machines where tensions are imposed on strands such as threads or the like.

10 In the drawings:

Fig. 1 is a view in vertical elevation showing one form of thread controlling means;

Fig. 2 is a view partly in section showing the means for supporting the vibrating thread tension levers;

Fig. 3 is a view in plan showing the thread controlling means;

Fig. 4 is a view in plan showing the arrangement of bobbins;

20 Fig. 5 is a detail view in plan showing how the threads are guided from the bobbins to the take-up levers;

Fig. 6 is a view in elevation of the construction shown at Fig. 5;

25 Fig. 7 is a view in elevation showing a modified form of thread controlling mechanism;

Fig. 8 is a view in plan disclosing the thread controlling means shown in Fig. 7;

30 Fig. 9 is a fragmentary view showing how a thread is locked, the view being relatively enlarged as compared with the same parts in Fig. 7;

Fig. 10 is a detail view similar to Fig. 9 but showing the parts in another relative position;

35 Fig. 11 is a detail view in elevation and corresponding to Fig. 9;

Fig. 12 is a view in elevation showing a fragment of the structure shown in Fig. 1, and showing a modified mechanism for controlling a 40 thread; and

Fig. 13 is a view in plan showing the modified mechanism disclosed in Fig. 12.

Referring first to the form disclosed in Figs. 1-5 inclusive, the mechanism indicated generally by the numeral 1 consists of a rotary unit adapted to rotate constantly in one direction or to oscillate by a gear connection (not shown), driven by means of a shaft 2 similar to that disclosed in the Lawson and Lawson patent. A 50 plurality of threads or yarns, such as 3, are shown as passing through eyelets such as 4 provided in a disc 5 which corresponds in structure and function to the disc 117 shown in the Lawson and Lawson patent.

55 Bobbins such as 6 are shown as being mounted

upon spindles 7 which in turn are mounted upon a plate 8 which constitutes part of a rotary unit. From the bobbin 6 the threads 3 pass upwardly through two circles of holes or eyelets 9 and 10, the said eyelets 9 and 10 thus being alternately arranged and in a staggered relation. After passing upwardly through the eyelets 9 and 10 the threads 3 then pass, in a tortuous path, between meshing gear-like members 11, 12 and 13, the first and last of which, however, do not 5 mesh with each other. The members 11, 12 and 13 are similarly constituted each being mounted on the shank of a shouldered screw 14 each screw passing through a hole in a plate 15 and being retained therein by means of a nut 16. 10 Each thread 3, as shown, passes between the meshing teeth of the gear-like members 11 and 12 and then at right angles through the meshing teeth 12 and 13, from there passing under a wire 17 secured to and spaced from the upper surface of plate 15, and then up and through an eyelet 18 provided in an end of a thread take-up and tension lever 19, the end being turned at substantially right angles to the shank of the lever 19. The levers 19 which are pivotally mounted on a split ring 20 adjacent to the axis of the rotary unit, extend outwardly therefrom in a radial direction. The split ring 20 passes through holes or slots 21 provided in a series of circularly arranged blocks 22 cast 25 integral with and constituting part of a plate or disc 23 made fast to plate 15. A screw 24 extends over the ends of the split ring 20 and retains the same in position as shown in Fig. 2. Intermediate the ends of the levers 19 are a 30 series of holes 25 any one of which is adapted to be engaged by one end of a coil spring 26 the other end of which is connected to a pin or screw 27, the pin 27 being mounted in the periphery of a plate 28 which is provided with a hub 29 40 retained in position on the rotary, hollow spindle 30 by means of a set screw 31. Obviously the force exerted by a spring 26 depends upon which hole 25 is engaged by the said spring, the greatest retractile force being exerted by the spring 26 when the spring is attached to the outermost of the holes 25. After passing through the eye 18 of the end of a lever 19, a thread 3 passes under the bar or wire 17 and then downwardly through an eyelet 32 provided in the plate 15, the thread 50 from there passing towards the axis of the spindle 30 and then through an eyelet 33 provided in the plate 8, the thread 3 then being guided in any suitable manner to and through an eyelet 4 in the disc 5. 55

By arranging the bobbin supporting plate or disc 8 beneath plate 15 upon which the yard tension means are mounted, and guiding the threads upwardly through the plate 15 and then between gear-like members 11, 12 and 13, and then radially inwardly and through the tension members 18 and then downwardly to and through the eyelets 4, an even tension is maintained on the threads which is not possible by 10 imposing tension on the threads through the medium of the usual tension discs, because the disc members being rotatable on a support, centrifugal force causes constant vibration of the discs, thereby causing the threads to be unevenly tensioned which consequently affects the knitting.

Referring to Figs. 7-11 inclusive, wherein a modified form of the invention is shown, the plate 15' and parts mounted thereon are modified somewhat as compared with the corresponding parts just described. The threads as before pass upwardly from bobbins 6 mounted on the plate 8, passing through one circle of eyelets 34 in the plate 15', each thread 3 then passing between bifurcated arms 35 of tension members 36 which are fastened to the plate 15' as by means of screws 37. Through the upper ends of the arms 35 of each member 36, a pin 38 passes, the said pin being retained in position by a screw 39 and serving as a pivotal support for 20 a lever 40. The arms 35 are recessed intermediate their lengths thus providing a shoulder 41 between which and the pin 42 a thread 3 is adapted to be clamped. A pin 42 is connected to and extends laterally from the arm 43 of the lever 40. The edges or surfaces of the arms 35 which are adjacent to the pin 42 when the same is in thread clamping position, are recessed or set back as indicated at 44 so that pin 42, when in the thread clamping position shown in 25 Fig. 9, will come to rest in contact with the thread 3 and shoulder 41 with the center of the pin 42 being directly above the edge defined by the shoulder 41 and beveled surface 45, the pin 42, however, not being in contact with the 30 adjacent edges or surfaces of the arms 35. A coil spring 46 which is adapted to be attached to any one of a series of holes 47 provided in the lever 40, is connected at its other end to the pin or screw 39. A turned end 48 of one 35 arm of a lever 40 engages the underside of lever 19 which is identical in all respects with lever 19 shown in Figs. 1 and 2. Although the holes 47 may also be utilized in the form shown in Figs. 7 and 8, nevertheless the spring adjustments are primarily obtained by attaching the coil spring 28 to the hooked end of a rod 49 which passes adjustably through a hole provided in a plate 28', a screw 50 serving to retain the rod 49 in adjustment position.

As hereinbefore stated, the threads 3 pass upwardly through circularly arranged eyelets 34 provided in the plate 15, and from there the threads pass more or less radially inwardly being yieldingly clamped between the pins 42 and 60 shoulders 41, the threads passing from there under bars or wires 51 which are carried by and mounted upon the upper surface of the plate 15 and then through the eyes 18 and finally down through a circular series of eyelets 52 which 65 are disposed inwardly with respect to the rods or wires 51. After passing through the eyelets 52, the threads are guided in a manner similar to or identical to that disclosed in Figs. 1 and 4.

When the needles impose tension on the 70 threads 3 or any of them, the corresponding

levers 19 are moved from the position shown in Fig. 7 to that shown in Fig. 10, whereupon the turned end 47 of a lever 40 is depressed thereby elevating the pin 42 from contact with the thread 3, thus permitting such threads 3 to be freely drawn by the needles of a knitting machine, or by other instrumentalities of a knitting or other machine.

A modified form of the invention disclosed in Figs. 12 and 13, consists of a detent or locking lever 53 which is pivoted intermediate its ends upon a pin 54 which latter passes through holes in opposed bifurcated arms in a stud 55, a pin or screw 56 passing through a hole in one of the arms and into engagement with the pin 54 to retain the same in position. The stud 55 terminates in a threaded shank which passes axially through the intermediate gear-like member 12, and though a hole in the plate 15 being retained in position by means of a nut 57. The outer arm of the lever 53 is provided with a right angularly extending end 58 which when the said lever is in the dotted line position of Fig. 12, moves in between adjacent teeth of the gear-like member 11 thereby positively locking the member 11 and consequently locking the members 12 and 13. While not essential during the knitting of stockings, it is desirable that, during the knitting of heels and toes or other reciprocatory knitting, the members 11, 12 and 13 be prevented from turning, thereby clamping the thread and preventing movement thereof.

The lever 53 is provided at the inner end thereof with an end 59 which extends substantially at right angles to the inner lever arm and is adapted to be engaged by means of a take-up lever 19 when the same is moved to a relatively lowered position by means of a thread 3. The movement of the lever 19 by the thread 3 to the relatively lowered position shown in Figs. 12 and 40 13, causes the end 58 of the outer lever arm to be withdrawn from between adjacent teeth of the gear-like member 11, consequently permitting the gear-like members 11, 12 and 13 thereafter to rotate freely when the needles cause the 45 thread to be drawn through the eye 18 of the lever 19.

The mechanisms hereinbefore described, while they impose sufficient tension on the threads 3, permit such threads to be fed freely to the needles or other instrumentalities, and without the 50 intermittent changes in tension which ordinarily result from the use of the usual thread tensions.

The rolls 11, 12, 13 shown in Figs. 1, 3, 5, 6, 12, 13, and the tension members, including the levers 19 and 40, shown in Figs. 7-11 inclusive, act positively to lock the threads and prevent them from being drawn from the source of supply, except when the needles or other instrumentalities impose a tension on a thread and either cause the 60 thread to be pulled through the gear-like members 11, 12, 13, or cause the pin 42 to be elevated, thereby permitting the threads to be drawn freely from the source of supply.

Although as hereinbefore described, the invention is particularly applicable to knitting machines of the type disclosed in the patent to Lawson and Lawson 1,702,608; the tension mechanisms may be used in split foot machines or in any knitting machines, the sensitiveness of the 70 tension being particularly useful in controlling the threads during reciprocatory knitting, e. g., the knitting of heels and toes of stockings or half hose.

While, in the foregoing description, the inven- 75

tion has been disclosed as being particularly adapted for use in knitting machines, and especially of the type disclosed in the Lawson and Lawson Patent 1,702,608; nevertheless, there is no intention of limiting the invention to any particular type of knitting or other machine.

I claim:

1. A thread controlling mechanism for knitting machines including thread supplying means and thread controlling means, the said thread controlling means permitting the thread or threads at times to pass freely to knitting instrumentalities and including a plurality of revoluble members between which the thread is adapted to pass, the said members having interengaging formations, thereby causing the thread to pursue a tortuous path, in combination with a movable arm which in one position acts upon the revoluble members to prevent passage of the thread to knitting instrumentalities.

2. Thread controlling means for knitting machines including thread supplying means and thread controlling means, the said thread controlling means permitting the thread or threads at times to pass freely to knitting instrumentalities and including a plurality of revoluble members between which the thread is adapted to pass, the said members having interengaging formations, thereby causing the thread to pursue a tortuous path, the thread controlling means also including a thread controlling finger through which a thread is adapted to pass, and a movable arm in association with said finger, said arm, at times, locking the said members and preventing movement of the thread therethrough.

3. A thread controlling means including two movably supported members, one such member being adapted to engage and clamp the thread and prevent movement thereof, the other member being provided with a thread guiding eye through which the thread passes and being movable from one position to another position by tension of the thread, the member last mentioned when moved to the second named position acting on the other member in such a manner as to permit the thread to be drawn freely through the mentioned thread guiding eye.

4. Thread controlling mechanism for knitting machines including a thread supplying means and thread controlling means, in combination with thread feeding means, the thread controlling means permitting the thread or threads to pass freely to knitting instrumentalities and including a thread clamp for temporarily retaining the thread and preventing its passage therethrough, said thread controlling means also including a member adapted to act on the aforesaid thread clamping means so as to release the thread from clamping engagement thereby to permit free movement of the thread through the clamping member.

5. Thread controlling mechanism for knitting machines including a source of thread supply and thread controlling means, in combination with means for feeding thread to the needles, the said thread controlling means including means adapted to permit thread to be drawn freely from the source of supply by knitting instrumentalities at all times and without imposing any drag on the said thread, but acting to lock the thread and prevent movement thereof when the knitting instrumentalities are not acting to draw thread from the thread supplying means.

75 6. Thread controlling mechanism including a

thread supply and thread controlling means, in combination with means for feeding threads to the needles of a knitting machine, said thread controlling means including a movable thread clamping member and a member associated therewith adapted, when the thread is under tension, so to act on the thread clamping member as to release the same from clamping engagement with a thread, the aforesaid member being movably mounted and the construction being such that a relatively short movement of the said member releases the clamp and permits the thread to be drawn freely by other instrumentalities without being retarded by engagement with the thread clamping member.

7. Thread controlling mechanism for knitting machines comprising a source of thread supply and knitting instrumentalities, the threads from which source are adapted to pass therefrom to the knitting instrumentalities, said threads, in their passage from the source of thread supply to the knitting instrumentalities, passing through thread controlling means, said thread controlling means comprising a rotatably mounted member having therein provisions for the passage of thread from the source of supply to the knitting instrumentalities, cooperating levers mounted upon the said member, one of said levers being pivoted adjacent to the periphery of the rotatably mounted member and extending inwardly toward the axis thereof, the other lever being mounted adjacent to the axis of the rotatably mounted member, and extending in a more or less radial direction and being maintained in constant engagement with the lever first mentioned, the lever first mentioned acting releasably to clamp a thread and the lever second mentioned acting, when the knitting instrumentalities are drawing thread from the source of supply to release the lever first mentioned in such a manner as to permit thread to pass freely from the source of supply to the knitting instrumentalities.

8. In a knitting machine rotary thread wrapping means mounted for rotary movement with which is a bobbin stand, in combination with thread controlling means connected with the bobbin stand so as to rotate therewith and including a movable thread clamping member, said thread controlling means preventing the threads from passing freely to the needles of the knitting machine when the needles are not knitting but operable to permit the threads to pass freely and without any drag to the needles upon resumption of knitting when the movable clamping member does not act to retard free passage of the thread to the needles.

9. In a knitting machine having a rotary means for wrapping threads around selected needles, a bobbin support and thread-tension means having a movable thread clamping member and rotatable with the thread-wrapping means, the thread passing from the bobbin support upwardly and through the thread-tension means and then downwardly through the thread-wrapping means and to the needles, the construction being such that when the needles are drawing thread from the source of supply the movable thread clamping member does not act to retard free passage of the thread to the needles.

10. In a knitting machine a source of thread supply, thread-tension means and thread-wrapping means all mounted so as to rotate on a common axis, the thread-tension means including a plurality of thread clamping members and levers pivoted adjacent to the said axis their outer

- ends being normally maintained in a relatively elevated position under spring tension, each thread clamping member being in association with one of the said levers, threads passing from the source of thread supply through the outer ends of the said levers and then to the thread-wrapping means, the construction being such that when the knitting instrumentalities are drawing a thread from the source of supply the movable clamping member does not retard free movement of such thread to the knitting instrumentalities.
11. A thread controlling mechanism for a knitting machine comprising a rotary unit having means for guiding a plurality of threads from a source of supply to the needles of the knitting machine, said unit including a series of like, movable members adapted to clamp and release the threads to maintain such threads under a proper degree of tension despite an occasional tendency to produce slackness in the threads during the knitting operation, and movable thread take-up means for each thread acting in conjunction with the clamping means to cause the same quickly to release the thread without engaging the thread in a manner to retard free movement of the thread to the needles, the construction being such that each thread clamping means after releasing the threads is quickly responsive to a slackness produced in the thread, the clamping means in such case acting quickly again to clamp the threads and thus maintain the said threads under a proper degree of tension.
12. A thread controlling means for a knitting machine including a support, a thread engaging take-up having a pivot and a clamping member pivotally mounted on the support and in cooperative relationship so that a temporary slack produced in the threads causes the take-up member to take up such slack and causes the clamping member quickly to clamp the thread and to prevent the take-up from pulling thread from the source of supply, the clamping member being engaged by the take-up member between the pivot of the take-up and its thread engaging portion.
13. A thread controlling means for a knitting machine including a support, a thread engaging take-up having a pivot and a clamping member pivotally mounted on the support and in cooperative relationship so that a temporary slack produced in the threads causes the take-up member to take up such slack and causes the clamping member quickly to clamp the thread and to prevent the take-up from pulling thread from the source of supply, the clamping member being engaged by the take-up member between the pivot of the take-up and its thread engaging portion, and the thread clamping member being pivoted in such a manner that a relatively long swinging movement imparted to the portion of the thread clamping member engaged by the take-up results in a short thread releasing movement being imparted to the thread clamping member so that upon slackness being produced in the thread the clamp will quickly re-engage the thread and prevent the movement of the take-up element from drawing thread from the source of supply.
14. A thread controlling mechanism for a knitting machine including a rotary support and a thread take-up mounted upon the rotary support adjacent to the axis thereof, a thread clamping member in association with the take-up and mounted outwardly thereof, the take-up and thread clamping member each including a lever
- in cooperative relationship, an outwardly disposed portion of the take-up lever having an eyelet through which the thread is adapted to pass on its way to the knitting machine and the thread clamping member having the clamping portion thereof so disposed with respect to the source of thread supply and the take-up that the thread may be engaged by the clamp before it passes through the eyelet of the take-up, the construction being such that upon a slackness in the thread being produced the take-up lever immediately takes up the said slackness and the clamp engages the thread to prevent the take-up from taking up more thread from the thread supply.
15. A knitting machine having a rotary wrap stripe mechanism associated therewith and in combination therewith and mounted to rotate with the wrap stripe mechanism, thread clamping and take-up means, the said means including two movable and cooperating elements, one for acting to take up slack thread and the other acting to work in conjunction with the take-up to engage the thread and prevent its being pulled from the source of thread supply by the action of the take-up as it moves to a position to take up the slack thread but being quickly responsive to the drawing of thread by the knitting instrumentalities to move to such a position to permit the thread to pass freely to the needles and without engaging the thread to retard the same.
16. A thread clamping means including a support and a thread clamping device mounted thereon, said clamping device consisting of a lever pivoted intermediate its ends to provide a long lever arm and a short lever arm, a cooperating lever in operative association with the long arm of the thread clamping lever and adapted to be moved by the pull of the thread as it is being knitted, the aforesaid operative association between the cooperating lever and the long arm of the thread clamping lever causing movements, imparted to the said cooperating lever by the pull of the thread, to move the thread clamping lever to such a position as quickly to release the thread and prevent the same being retarded by the clamp, and the lever action due to the construction of the two cooperating levers being such as to permit the clamp quickly to re-engage the thread upon a temporary slackness being produced in the thread thereby preventing more thread from being drawn from the source of thread supply.
17. A rotary support for use in a knitting machine having a thread take-up lever pivotally mounted thereon adjacent to the axis and having a thread clamping lever pivotally mounted outwardly of the pivotal support of the take-up, one end of the take-up lever extending in the direction of the thread clamping lever and the thread clamping lever extending in the direction of the pivot of the take-up lever.
18. A rotary support for use in a knitting machine having a thread take-up lever pivotally mounted thereon adjacent to the axis and having a thread clamping lever pivotally mounted outwardly of the pivotal support of the take-up, one end of the take-up lever extending in the direction of the thread clamping lever and the thread clamping lever extending in the direction of the pivot of the take-up lever, an eyelet being provided in the thread take-up lever at a point substantially removed from the pivot thereof, the take-up lever being in engagement with the clamping lever and at a point nearer to the

axis of the take-up lever than to the thread engaging portion thereof so that movements of the take-up lever induced either by a slackness in the thread or by the traction exerted by the knitting instrumentalities upon the threads results in the clamping portion of the lever being moved a relatively short distance as compared with the distance through which the thread engaging end of the take-up lever moves under the conditions 10 named so that the clamp may quickly re-engage the thread after it has been released from such engagement.

19. A support for a thread controlling mechanism of a knitting machine, and thread clamping and take-up levers mounted thereon, the two levers being maintained in engagement so that movements of the take-up lever are transmitted to the thread clamping lever in such a manner as to permit the clamp quickly to release and re-20 engage the thread, the lever construction and engagement being such that a relatively slight pull exerted upon the thread by knitting instrumentalities causes the clamp to release the thread.

20. A support for a thread controlling mechanism of a knitting machine, and thread clamping and take-up levers mounted thereon, the two levers being maintained in engagement so that movements of the take-up lever are transmitted to the thread clamping lever in such a manner 30 as to permit the clamp quickly to release and re-engage the thread, a thread clamping element fixedly mounted on the support and having a downwardly sloping portion to act in conjunction with the cooperating portion of the thread clamping lever.

21. A thread controlling means including two movably supported members, one such member being pivoted intermediate its ends to constitute a lever and one arm of the said lever adapted to 40 engage and clamp the thread and prevent movement thereof, the other member being provided with a thread guiding eye through which the thread passes and being movable from one position to another position by tension of the thread, 45 the member last mentioned engaging the other arm of the thread clamping lever and, due to such engagement, the said other member when moved to the second named position acting on the lever in such a manner as to permit the thread to be drawn freely through the mentioned thread guiding eye.

22. A thread controlling device for a knitting machine including an arm movable in response to variations in the tension imposed upon the 55 thread during knitting, a portion of the said arm acting to clamp the thread, and a thread clamping member adapted to cooperate with the thread clamping portion of the said arm to prevent movement of the thread from the source of supply and in the direction of the needles except when the knitting of the thread by the needles of the knitting machine acts to draw thread from the source of supply, the surface of the cooperating thread clamping member adjacent to the 60 thread clamping portion of the said arm when the arm is in thread clamping relation with respect to the cooperating thread clamping member, sloping downwardly so that the clamping portion of the arm, upon its initial movement 65 away from the cooperating thread clamping member, permits the passage of enlarged portions of the thread, such as knots, thus avoiding the possibility of breaking the thread.

23. A thread controlling device for a knitting 70 machine including a member movable in response

to variations in the tension imposed upon the thread during knitting, a thread clamping member adapted to cooperate with a portion of the said movable member to prevent movement of the thread from the source of supply and in the direction of the needles except when the knitting of the thread by the needles of the knitting machine acts to draw thread from the source of supply, the surface of the cooperating thread clamping member adjacent to the thread clamping portion of the said movable member when the member is in thread clamping relation with respect to the said cooperating member, sloping downwardly so that the movable member, upon its initial movement away from the cooperating 10 thread clamping member, permits the passage of enlarged portions of the thread, such as knots, thus avoiding the possibility of breaking the thread.

24. A thread controlling device for a knitting machine including a lever and means for pivotally supporting said lever, said lever being engaged by a thread in its passage from the thread supply to the needles of the knitting machine, a second lever having a thread clamping portion, 20 said second lever being engaged and moved by the lever first mentioned, a cooperating thread clamping member adapted to cooperate with the thread clamping portion of the second mentioned lever to prevent movement of the thread from the source of supply and in the direction of the needles except when the knitting of the thread by the needles of the knitting machine acts to draw thread from the source of supply, the surface of the cooperating thread clamping member adjacent to the thread clamping portion of the lever when the said lever is in thread clamping relation with respect to the said cooperating member, sloping downwardly so that the said lever, upon its initial movement away from the cooperating member, permits the passage of enlarged 30 portions of the thread, such as knots, thus avoiding the possibility of breaking the thread.

25. A thread controlling mechanism for a knitting machine, said mechanism including a support and a pair of cooperating arms movably mounted thereon, one of said arms having a portion adapted, when in one position, to arrest the free passage of the thread to the needles of the knitting machine, the other arm having provision for the passage therethrough of the thread, the construction being such that when a movement is imparted to the arm second mentioned by means of the thread, the said second mentioned arm engages the arm first mentioned and causes 40 such a movement thereof as to permit movement of the thread in the direction of the needles, passage of the thread to the needles being prevented when the arm second mentioned moves out of cooperative relationship with the arm first 45 mentioned.

26. A thread controlling mechanism for a knitting machine, said mechanism including a support and a pair of cooperating arms movably mounted thereon, one of said arms having a portion adapted, when in one position, to clamp the thread and prevent the free passage thereof to the needles of the knitting machine, the other arm having provision therein for the passage therethrough of the thread, the construction being such that when a movement is imparted to the arm second mentioned by means of the thread, the said second mentioned arm engages the arm first mentioned and causes the same to release the thread from clamping engagement 55

thus permitting free movement of the thread in the direction of the needles, the aforesaid clamping of the thread being effected when the arm second mentioned moves out of cooperative relationship with the arm first mentioned.

27. A thread controlling mechanism for a knitting machine, said mechanism including a support and a pair of cooperating arms movably mounted thereon and a spring acting upon one of the said arms, one of said arms having a portion adapted, when in one position, to arrest the free passage of the thread to the needles of the knitting machine, the other arm having provision for the passage therethrough of the thread, the construction being such that when a movement is imparted to the arm second mentioned by means of the thread, the said second mentioned arm engages the arm first mentioned and causes such a movement thereof as to permit movement of the thread in the direction of the needles, passage of the thread to the needles being prevented when the arm second mentioned moves out of cooperative relationship with the arm first mentioned, such movement of the arm second mentioned out of cooperative relationship with the arm first mentioned being effected by the spring.

28. A thread controlling mechanism for a knitting machine, said mechanism including a support and a pair of cooperating arms movably

mounted thereon and a spring acting upon one of the said arms, one of said arms having a portion adapted, when in one position, to clamp the thread and prevent the free passage thereof to the needles of the knitting machine, the other arm having provision therein for the passage therethrough of the thread, the construction being such that when a movement is imparted to the arm second mentioned by means of the thread, the said second mentioned arm engages the arm first mentioned and causes the same to release the thread from clamping engagement thus permitting free movement of the thread in the direction of the needles, the aforesaid clamping of the thread being effected when the arm second mentioned moves out of cooperative relationship with the arm first mentioned, such movement of the arm second mentioned out of cooperative relationship with the arm first mentioned being effected by the spring.

29. A thread controlling mechanism for a knitting machine including a support, a plurality of spaced thread engaging members pivotally mounted upon the support, the pivotal mounting including a ring and a slot in the support within which slot the ring is seated, and means for retaining the ring in the slot, the ring serving as a pivot for all of the thread engaging members.

ROBERT H. LAWSON. 30
